UNITED STATES PATENT OFFICE

WILLIAM HENRY OWEN, OF LONDON, ENGLAND

HEAT EXCHANGE APPARATUS

Application filed October 4, 1929, Serial No. 397,368, and in Great Britain December 21, 1928.

This invention relates to heat exchange apparatus of the kind in which a self-contained unit comprising a bundle of cells is mounted in the conduit of a hot fluid medium, for the purpose of utilizing the heat thereof.

The invention is more particularly intended for apparatus for pre-heating air for combustion in furnaces by means of the heat contained in the hot flue gases.

In connection with air pre-heating devices for furnaces, it is already known to provide a heat exchange apparatus comprising a bundle of plates held together by transverse bolts and shaped, or otherwise adapted to form spaced cells through which is passed the air requiring to be heated, the unit being positioned in a conduit for combustion products so that these are required to pass through the narrow inter-cellular spaces whereby they give up a certain quantity of heat through the plates to the air passing through the cells.

Such units have inlet and outlet ports for the air situated along the same face, and they require to be mounted or secured against the wall of the conduit for the combustion products with a closed joint and preferably in a manner permitting ready dismantling in case of need.

It will be appreciated that in many cases the unit is of considerable weight, requiring mechanical power to lift and transport, and that when in position, the weight is taken by resting the unit on a supporting surface.

Now according to the present invention, the unit is adapted to be drawn tightly against the wall of the conduit by means of eye-bolts or of hook-bolts with screwed shanks passed through holes in abutment bars engaged behind fixed members mounted in the wall. It is to be understood that the bolts are loose relatively to one or both of the parts requiring to be assembled so that they can be set up and secured in any desired position after the parts have been assembled, and no adjustment of the position of the heating unit e. g. lifting slightly or rocking a little, is necessitated in order to render the bolts attachable since they can be attached in any casual position of the unit within the ordinary limits permitting performance of its functions.

Nuts are mounted on the shanks, and on tightening up the said nuts the unit is engaged against the supporting surface with the necessary tightness.

The following description, however, will be applied to air pre-heating apparatus for furnaces, by way of example. The invention is illustrated in the accompanying drawings in which

Fig. 1 illustrates a perspective view, and
Fig. 2 a part sectional elevation,
Figs. 3 and 4 being views of details.

Referring now to the drawings, 1 presents the heat exchange unit formed of bundles of plates and having outlet and inlet ports 2, 3 for the air or other medium requiring to be heated. Within the area of the said ports the plates are held together by transverse through bolts 4. In Figure 1 the plates are shown broken away within the ports so as to illustrate the bolts more clearly. 5 illustrates a framing formed of iron sections, which is built in the wall of a conduit and with which the unit 1 is required to be tightly engaged. The framing includes two vertical pillars 6 of T section, but it will be understood that with constructions of smaller capacity than that illustrated this detail may be varied.

According to the invention, one or more abutment bars 7 are laid across the flanges of the T section 6, and the threaded shanks of hook-bolts 8 are passed through holes in said bars. When the unit 1 is in position, the hook-bolts 8 are engaged in each case over one of the bolts 4 and by tightening up nuts 9 behind the abutment bar 7 the unit 1 is held against the frame 5 with sufficient tightness substantially to close the joint.

It will be understood that although in the form shown only one bar 7 is utilized in each port, a plurality of bars and bolts may be utilized if found necessary and desirable. Further, the application of this invention is not limited to those cases where through bolts are used for assembling the bundles of cells as it is obvious that special bolts or other suitable attachments may be provided for engaging with the hook-bolts.

It will be understood that the weight of the unit 1 is supported by any suitable means

not illustrated in the figure, and that the hook-bolts 8 only control the horizontal approach of the unit to the framing. The bars 7 do not require to be fixed to the framing, 5 but are simply laid across the flanges of the T section members 6 for adjustment in the required position opposite to the selected bolt 4. Thus the bolts can be fixed up at any 10 levels where the cross-bars 4 happen to be situated, and the position to which the heating unit has been adjusted does not need to be changed even slightly for the mere purpose of setting up the bolts.

It is to be understood that with the form 15 illustrated the air conduit 10 to which the port 2 is required to give access is of substantial height usually sufficient to permit a workman to enter therein for the purpose of anchoring the units. In Figure 2 I have illustrated an arrangement in which two sets 20 of units are set up one on each side of a central air conduit 10, as this shows a construction for large units, but obviously for small units the arrangement may be suitably 25 modified. With substantially smaller units where T sections 6 do not form a usual part of the construction, the bars 7 may be laid behind any suitable portion of the edge of the conduit 11 for the products of combustion 30 e. g. behind a rail laid behind the brick-work.

Usually I prefer to employ hook-bolts for convenience in attachment, but especially with smaller units eye-bolts may be provided 35 which, of course, will be set up in position in the units during their manufacture.

I claim:

1. In combination with a conduit, a heat 40 transfer unit having spaced ports to register with the ports formed in the conduit, a framing carried by the conduit to receive the heat transfer unit, members loosely engaging the framing, and tensioning means located in said ports and connected to the heat transfer 45 unit and cooperating with said members to support the heat transfer unit in fixed relation to the framing.

2. A heat transfer unit having spaced 50 ports, a conduit formed with openings with which said ports are adapted to register, a framing carried by the conduit, bars loosely engaging the framing, and tensioning means intermediate the bars and unit to hold the latter in fixed relation to the framing, said 55 means fixing the bars with respect to the framing.

3. A heat transfer unit formed with spaced 60 ports, a conduit having openings with which the ports are adapted to register, a framing carried by the conduit and presenting longitudinal strips, abutment bars loosely bearing against said strips, and means to be removably connected to the unit and to said bars to hold the unit and bars in fixed relation to the framing.

4. A heat transfer unit formed with spaced ports, a conduit with openings with which the ports are adapted to register, a framing secured to the conduit and presenting strips bridging the openings in the conduit, bars 70 loosely bearing against said strips on the conduit side thereof, and means rigidly connecting said bars and unit, said means serving to bind the unit in contact with the framing to hold the bars rigidly with respect to the strips.

5. A heat transfer unit having spaced ports, rods extending across said ports, a conduit formed with openings with which the ports of the unit are adapted to register, a framing 80 defining the openings in the conduit and including strips bridging the openings, bars loosely bearing against the conduit side of the strips, hook members to removably engage the rods of the unit and pass through 85 said strips, and securing means cooperating with the hooks beyond the bars to draw the unit into contact with the framing and hold the bars rigidly with respect to the framing to provide rigid securing means for the unit.

In testimony whereof I affix my signature.
WILLIAM HENRY OWEN.
